HERBERT T. CHERRY AND JAMES R. CARTER, OF TAMA, IOWA, ASSIGNEES TO J. G. CHERRY COMPANY, OF CEDAR RAPIDS, IOWA, A CORPORATION OF IOWA.

CELL-CASE.

1,326,184.

Specification of Letters Patent. Patented Dec. 30, 1919.

Application filed June 25, 1919. Serial No. 303,538.

To all whom it may concern:

Be it known that we, HERBERT T. CHERRY and JAMES R. CARTER, citizens of the United States, both residing at Tama, in the county 5 of Tama and State of Iowa, have invented certain new and useful Improvements in Cell-Cases, of which the following is a specification.

It is a common practice to ship eggs in 10 quantities packed in individual cells in cell cases which are separated from each other by flats in a suitable crate or box. In shipment the cases or crates are often subjected to rough usage, causing the cell walls to 15 yield or collapse and the cell cases to shift bodily in the crate or box and resulting in more or less damage to the cell cases and the eggs. Various means have been suggested for bracing the cell walls, but these have 20 usually involved specially designed cases or more or less complicated constructions which are too costly to be commercially practicable or are otherwise objectionable. Efforts have also been made to prevent the cell cases 25 from shifting in the crate or box by extending the ends of the intersecting wall strips beyond the outer strips of the case to form buffers which engage the sides of the crate or box, and while this has undoubtedly re- 30 duced the liability of shifting to some extent it has not proven entirely sufficient.

It is customary to pack thirty dozen eggs in a crate or box and to use the cell cases and flats but once. Consequently these cell 35 cases and flats must be made of simple construction so that they can be used by unskilled persons and they must be sold at low cost since they are seldom if ever used a second time.

40 The object of our invention is to provide a flat of novel form and strong construction which can be engaged with a cell case to reinforce and strengthen the sides of the individual cells and to protect the case as a 45 whole against bodily shifting movement in a box or crate.

A further object of our invention is to 50 provide a flat which can be readily engaged with cells of any standard construction, which will occupy no more space than an ordinary plain flat and which can be produced at low cost.

In the accompanying drawings illustrating the invention

55 Figure 1 is a perspective view of a cell

case showing a preferred form of the flat engaged therewith;

Fig. 2 is a sectional view on the line 2—2 of Fig. 1;

Figs. 3, 4 and 5 show other forms of the 60 flat.

Referring to the drawings, 6, 7 designate a plurality of intersecting and interlocking strips which form the case comprising a plurality of individual cells. Our invention 65 is not limited to a cell case constructed in any particular manner but it is adapted for use with all kinds of standard cell cases, as will be readily understood. In these cell cases the ends 6', 7' of the strips project 70 beyond the outer strips of the case to form buffers which engage the walls of the crate or box in which the cases are packed, one above the other, with a flat on the top of each cell case in the usual manner.

Our improved flat 8 comprises a sheet of straw-board or other suitable material which is provided at intervals with one or more longitudinal depressions 9 extending in parallel relation from one end of the sheet 80 to the opposite end thereof. Between these depressions there is a flat section 10, the arrangement being such that when the flat is placed in position upon a cell case, as shown in Fig. 1, the depressions 9 will be located 85 between the cell strips 7, running in one direction and the flat sections 10 will rest on said strips and also on the strips 6 at the intersections. In the preferred form of the

invention illustrated in Figs. 1 and 2 the depressions are comparatively wide and shallow and the flat sections are about as wide as the depressions, making, in effect, a corrugated flat. The depressed corrugations 9 are provided with slits 11 at intervals to engage the cell strips 6 so that the depressed portions of the entire flat within the outer walls of the case will lie within the cells, and the intermediate portions will rest upon the top of the case. These corrugations may be 90 made in a variety of ways, some of which we have shown in the drawings. In Fig. 3 there are two narrow corrugations 12 with an intermediate wide corrugation 13; in Fig. 4 there are three corrugations 14 of the 95 same general width and shape, and in Fig. 5 there is an angular corrugation 15. We do not limit ourselves to the particular number or to the shape of the corrugations employed but, as before stated, there are cer-

tain advantages derived from the form shown in Figs. 1 and 2 which we think make it desirable. This form is comparatively easy to make, the wide corrugations engage the wall strips for a considerable length to reinforce and strengthen them and the flat sections 10 form ample support for the wall strips which engage therewith. However, satisfactory results may be obtained with 5 flats otherwise corrugated, as heretofore stated, and we do not limit the invention to any particular form so long as the flat is constructed to rest upon the upper edges of the wall strips running in one direction and 10 to engage the wall strips running in the other direction at each of the cells of the case. The flat is made of sufficient size to project beyond the outer wall strips of the case a distance corresponding to that of the buffer 15 ends 6', 7' so that the edges of the flat will engage the walls of the crate or box like these buffers. The corrugated edges of the flat are much stronger than the plain edges and consequently the flat is strengthened 20 at these edges which not only tends to preserve the flat itself but also materially strengthens the case and prevents the case from shifting in the direction of the corrugations. If the flats in a crate or box are 25 arranged with their corrugations running alternately lengthwise and crosswise it will be seen that the entire stack of cases will be reinforced by the flats and strengthened at the edges against bodily shifting movement. 30 35 In practice a flat is arranged on top of each cell case and it will be readily understood that by the corrugated form of the flat and the interlocking engagement of the flat with the wall strips of the cell case, the 40 walls of each cell and the case as a whole are made much stronger and more rigid. The cell walls which are interlocked with the flat by engagement with the slits therein are materially strengthened and the other 45 walls are also strengthened by reason of this interlocking engagement and by the intermediate section between depressed corrugations resting thereon. While we have found it desirable to make this intermediate 50 section flat, substantially as shown in Figs. 1 and 2, we appreciate the fact that it may be made curved like an ordinary corrugation, and the depressed corrugations similarly made if so desired, and we contemplate 55 this form as a part of our invention and within the scope of our claims.

The improved flat can be produced at very low cost because of its simple construction and we particularly direct attention to 60 the fact that it can be used with any standard form of cell case, in fact any form which has no projections above the plane of the top of the cells and with which the slotted corrugations may be engaged and interlocked. 65 This is a desirable feature of the invention

because it does not depend in any way upon any particular manner of interlocking the cell wall strips or to cell cases of any special construction.

When a plurality of these cell cases are 70 arranged one upon the other, with interposed flats within a crate or box, the depressed corrugations in the flat on the top of one case will form seats for the eggs in the case resting on that flat. And while our 75 invention is particularly adapted for cell cases for shipping eggs it may be adapted for many other articles which are shipped in cell cases.

We are aware that changes in the form 80 and construction of parts may be made, some of which have been pointed out, without departing from the spirit of our invention and we reserve the right to make all such changes as fairly fall within the scope 85 of the appended claims.

We claim:

1. The combination of a cell case comprising a plurality of intersecting and interlocking wall strips forming cells therebetween, and a flat arranged on said case and having parallel depressions with transverse slits therein to engage opposite wall strips of said cells and intermediate plain sections to rest upon the other wall strips 90 of the cells.

2. The combination of a cell case comprising a plurality of intersecting and interlocking wall strips forming cells therebetween, and a flat having spaced slits to 100 engage the edges of opposite wall strips of said cells, that portion of the flat between each pair of slits being depressed to fit between the wall strips engaged by said slits.

3. The combination of a cell case comprising a plurality of intersecting and interlocking wall strips forming cells therebetween, and a flat arranged on said case and consisting of a sheet having corrugations extending in one direction forming parallel 105 altering depressions and elevations, said depressions having transverse slits extending through the sheet to receive edge portions of opposite wall strips so that said depressions will lie below the plane of the 110 upper edges of the strips and the elevations will lie above the plane of the upper edges of the strips.

4. The combination of a cell case comprising a plurality of intersecting and interlocking wall strips forming cells therebetween, the ends of said strips projecting beyond the outside walls of the case to form buffers, and a flat arranged on said case with its edges projecting beyond the outside 125 walls of the case to correspond with said buffers, said flat having depressions in opposite edges to lie between adjacent buffers and plain sections between said depressions to engage said buffers.

5. A flat for a cell case consisting of a sheet having a plurality of parallel depressions therein extending in one direction, said depressions being slotted transversely at spaced intervals.
5 at spaced intervals.
6. A flat for a cell case consisting of a sheet having a plurality of parallel alternating depressions and plain sections extend-

ing in one direction, said depressions being slotted transversely at spaced intervals.
